OSCAR ONSRUD, OF CHICAGO, ILLINOIS, ASSIGNOR TO L. L. VALENTINE, OF CHICAGO,
ILLINOIS

AIR DRIVEN COTTON PICKER HEAD

Application filed September 18, 1926. Serial No. 135,059.

Cotton has been successively harvested by means of a picker head secured to the end of a suction pipe and containing revolving brushes or other elements adapted to pull the cotton fibre from its seats in the boll and deliver it into the rearwardly flowing air current passing through the suction pipe. These picker heads must be comparatively light in order to permit them to be manipulated by the operator to bring them quickly and easily into proximity to one boll after another and into different positions with respect to each individual boll. Therefore it is necessary that the driving means for the moving elements in such a head be of a type that will not make the head unduly large or heavy or interfere with the free bodily movement of the head during the harvesting operations. Small electric motors mounted on the head, and long flexible shafts extending along the suction conduits have both been used for driving the mechanism in the head, but neither has been fully satisfactory.

The object of the present invention is to provide a picker head with a novel driving mechanism that will not add greatly to the size or weight of the head, and that has no parts subject to appreciable wear or apt to get out of order so as to require the attention of an expert mechanic. Or, viewed in another aspect, my invention may be said to have for its object to provide a picker head with a simple light and compact motor that is efficient and reliable in operation and possesses great ruggedness and durability, so as to be practically fool-proof in the hands of ignorant persons using the head for harvesting cotton.

Another object of the present invention is to simplify and improve the construction of one of the most successful types of picker heads as a whole.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a front view of a picker head constructed in accordance with the present invention; Fig. 2 is a partial transverse section taken approximately on a plane passing through the axes of the rotating brushes; Fig. 3 is a section at right angles to the plane of Fig. 2, through one of the caps that serve as bearings for the upper ends of the brushes, together with fragments of the casing and of one of the brushes; Fig. 4 is a top plan view of a fragment of the cap shown in Fig. 3, together with a portion of the casing surrounding the cap; Fig. 5 is a section taken approximately on line 5—5 of Fig. 2; and Fig. 6 is a section taken approximately on line 6—6 of Fig. 5.

Referring to the drawings, 1 represents a hollow casing tapering from the front toward the rear where it terminates in a cylindrical neck or sleeve 2 adapted to be inserted in the end of a suction conduit 3. The front end of the casing has therein a large mouth or opening 4 as is usual in devices of this kind. Arranged within the casing, in rear of the mouth or opening, are two parallel rotatable brush-supporting bodies or cores, 5 and 6, extending between the top and bottom walls of the casing. The members 5 and 6 may conveniently take the form of wooden cylinders fitted upon squared portions 7 of a pair of vertical shafts 8 and 9. Each core has undercut grooves 10 distributed about the same and extending from end to end. Into these grooves are slidably fitted brush backs 11 to which are fixed projecting bristles 12. The members 11 of each unit are held in place by means of two sleeves 13 fitted over the ends of the core and reduced end portions of the member 11. Each sleeve has a flaring outer end 14. The sleeves are held in place, each by a screw 15 introduced into the end of the core, close to the periphery of the latter, so that the heads of the screws overlap the flaring ends of the sleeves somewhat.

The top of the casing has round openings 95 directly above the brushes, each large enough to permit the withdrawal of an entire assembled brush unit. These openings are closed by means of disc-like caps 16 having on their undersides central bearings 17 to receive the 100

cylindrical upper ends 18 of the brush shafts. The top wall of the casing is undercut, as indicated at 19, around the openings therein, and the caps are provided with lips that project laterally slightly from the bottom thereof for the purpose of underlying the undercut portions around the openings. These lips may conveniently be produced by passing rivets 20 through each of the caps near the margins, and flanging the lower or inner ends of the rivets so as to cause them to project slightly beyond the peripheries of the caps. In the arrangement shown, there are two of these rivets, arranged diametrically opposite each other. In order to permit the locking lips to pass up and down through the openings in the casing, notches 21, one of which is shown in Fig. 4, are cut at opposite sides of each of the openings. In order to apply one of the caps, it is positioned over one of the openings, with the locking lips registering with the notches. The cap is then lowered and turned through a small angle in either direction, until the locking lips pass underneath the overhang. Each cap may be provided with a pair of ears 22 projecting upwardly from the top of the same, to which ears a tool or other implement may be applied for the purpose of turning the cap. When one of the brush units is to be removed, the corresponding cap is turned until its locking lips are brought up opposite the notches at the sides of the opening in the casing, and the cap may then be lifted off. After the cap has been removed, the brush unit may be lifted bodily from the shaft on which it is mounted, leaving the shaft in the casing. Any individual brush may be removed from the unit, by detaching one of the sleeves that holds the brushes in place, and then sliding the brush endwise out of its groove.

The parts are so proportioned that the flaring ends of the sleeves on the brush units bear against the under faces of the caps, at the top, and against the bottom wall of the casing, at the bottom. Cotton or other material is thereby prevented from entering the bearings for the brush shafts. In order to make it still more difficult for foreign matter to gain access to the shafts, the ends of each brush-supporting core are countersunk, as indicated at 23. Each cap has a flange 24 extending downwardly into the recess in the top of the corresponding core, and the bottom wall of the casing has two sleeves, 25 extending upwardly into the recesses in the lower ends of the cores.

The two brush shafts extend downwardly through the sleeves 25 into a chamber 26 on the underside of the casing. In the lower portion of this chamber are suitable ball bearings 27 for the shafts and, on each shaft, above such bearing, is fixed a gear wheel 28. The two gear wheels mesh with each other, and one of them meshes with a driving pin-

ion 29 on the upper end of a turbine shaft 30 that extends downwardly through the lower wall of the chamber 26 and into an underlying turbine casing 31. The turbine shaft is supported by ball bearings 32 and 33 located respectively in the top and bottom of the turbine casing. Fixed to the turbine shaft between its bearings, is a turbine wheel 34. The turbine casing is provided with an inlet nipple 35 lying below the neck 2 of the picker head. Within the turbine casing is a nozzle 36 connected at its outer end with the nipple and having its inner end positioned to direct a stream of air against the turbine wheel. Air may be supplied, for rotating the turbine, through a suitable conduit, not shown, attached to the nipple.

The exhaust from the turbine may be utilized to assist in carrying the cotton rearwardly into the suction conduit. In the arrangement shown, the main casing is enlarged at the front end of the contracted neck 2, so as to produce an annular groove 37 extending entirely around the head. This groove is closed by means of a ring 38 fitted into the head and having a series of small ports or passages 39 drilled through the same at points distributed around the ring and extending through the latter in such directions that their long axes converge at the long axis of the head at some point in rear of the ring. The groove 37 communicates with the interior of the turbine casing through a passage 40, whereby the exhaust may pass from the turbine casing into the annular groove and then be discharged rearwardly at the rear of the head, in the form of converging jets.

As is usual in constructions of this kind, suitable guard fingers 41 are placed in the mouth of the picker head, in front of the brushes. Other guard fingers 42 are placed in the side openings 43 formed in the picker head in rear of the brushes. To the ring 38 are attached rearwardly extending, converging guard fingers 44 that will prevent twigs or the like from being carried rearwardly into the suction conduit.

Assuming that the suction conduit is connected to a blower, and that air under pressure is being delivered through the nozzle 36 in the turbine, the turbine will be rotated at a high speed and the brushes will be driven in opposite directions at a lower speed, through the reduction gearing between the same and the rotor of the turbine. If now a cotton boll is brought close to the mouth of the picker head, the brushes will pull the fibre from the same and discharge it rearwardly into the head. The air that is being drawn through the mouth of the picker head and the openings in rear of the brushes, picks up the cotton and carries it rearwardly into the suction conduit. As the cotton enters the

contracted neck at the rear end of the head, it is subjected to the action of the jets from the exhaust of the turbine in such a manner that its speed of travel is increased. In any event, the action of the jets is to blow the cotton rearwardly, away from the head, and insure that it will not stick between the fingers 44 and clog the apparatus.

It will be seen that the addition of the 10 turbine to the picker head adds very little to the weight of the latter, since the bottom of the head forms the top wall of the turbine casing and, in addition to the casing, the only other added parts are the comparatively light 15 rotor and the bearings therefore. The size of the picker head is not greatly increased by the addition of the turbine, the casing for which has very little depth and a diameter such that it does not project beyond the head 20 in a lateral direction. It will be seen that the mechanism of the turbine consists of a simple rugged rotor and, the bearings of which are effectually housed against the entrance of dust and other foreign matter; so 25 that there is nothing to get out of order, and the head may be used indefinitely by common laborers without any diminution in efficiency. A simple, small flexible air pipe, extending along the large conduit, will serve 30 to supply air to the turbine, without in any way interfering with the freedom of movement of the head as a whole. The head may therefore be manipulated freely and without causing fatigue to the user, and is practically 35 indestructible even though little or no care is exercised in handling it. As a matter of fact, the only parts that are subject to appreciable wear are the brushes, and my improved means for mounting these permits 40 them to be readily removed and renewed.

While I have illustrated and described with particularity only a single preferred form of my invention, I do not desire to be limited to the exact structural details thus illustrated and described; but intend to cover all forms and arrangements which come within the definitions of my invention constituting the appended claims.

I claim:

50 1. A picker head comprising a casing having an inlet and an outlet, rotary picker elements arranged in the head adjacent to the inlet and having shafts extending through one of the walls of the head, members 55 operating with each other and with the latter wall to form a turbine casing and between said wall and the casing a gear chamber, a turbine shaft extending into said gear chamber, and gearing in said chamber between 60 the turbine shaft and the picker element shafts.

65 2. A picker head comprising a casing having three chambers lying above each other, the upper chamber having an inlet mouth and an outlet, rotary picker elements in the

upper chamber having shafts extending into the intermediate chamber, a turbine wheel in the lower chamber having its shaft extending upwardly into said intermediate chamber, and gearing in said intermediate chamber 70 connecting said shafts together.

3. A picker head comprising a hollow casing, a pair of parallel brush units extending across said casing, the wall of the casing at one end of the units having large openings 75 concentric with and of a size to permit the passage of said units, caps closing said openings, and bearings in the caps for the adjacent ends of the units.

4. A hollow picker head having a rotatable 80 brush unit therein, there being an opening in the wall of the head opposite one end of the said unit large enough to permit the said unit to pass through the same, a cover for said opening constituting also a bearing for 85 the adjacent end of the brush unit, and shoulders on the cover and the head adapted to interlock with each other when the cover is turned to hold the cover in place.

In testimony whereof, I sign this specification.

OSCAR ONSRUD.
